UNITED STATES PATENT OFFICE.

HARRY H. CLARK, OF DETROIT, MICHIGAN.

AUTOMOBILE-SNOWPLOW.

1,365,153.

Specification of Letters Patent. Patented Jan. 11, 1921.

Application filed October 16, 1918. Serial No. 258,421.

To all whom it may concern:

Be it known that I, HARRY H. CLARK, a citizen of the United States, residing at Detroit, in the county of Wayne, State of Michigan, have invented certain new and useful Improvements in Automobile-Snowplows; and I do hereby declare the following to be a full, clear, and exact description of the invention, such as will enable others skilled in the art to which it appertains to make and use the same.

This invention relates to new and useful improvements in snow plows and particularly to snow plows which are arranged for attachment to automobiles.

One object of the present invention is to provide a novel and improved device of this character which can be easily and quickly attached to or removed from any automobile and which will clear the road, ahead of the automobile, of snow.

Another object is to provide a novel and improved device of this character whereby snow to the required depth can be removed for the purpose of exposing or leaving a sufficiently shallow and hard surface for the traction of the drive wheels of the automobile.

Another object is to provide a novel and improved device of this character which will readily ride up over obstructions in the road, whereby danger of breaking the plow is eliminated.

A further object of the invention is to provide a novel and improved device of this character whereby the depth of the snow to be removed can be easily and efficiently regulated.

Other objects and advantages will be apparent from the following description when taken in connection with the accompanying drawing.

In the drawing:

Figure 1 is a top plan view of the front portion of an automobile showing my invention applied thereto.

Fig. 2 is a side elevation of the same.

Fig. 3 is a vertical transverse sectional view taken on the staggered or irregular line 3—3 of Fig. 1.

Fig. 4 is a vertical longitudinal sectional view taken on the line 4—4 of Fig. 1.

Referring particularly to the accompanying drawing, 10 represents the front axis of the automobile, 11 the radiator, and 12 the filling tube of the radiator, in connection with

which my invention is particularly adapted for use.

Disposed on the front axle, and secured thereto by means of the U-bolts 13, are the plates 14, each having its forward end bifurcated, as at 15, and receiving therein the rear end of an arm or link 16. This arm is pivotally connected in the bifurcation so that said arm will swing in a vertical plane, as will be plainly seen from an inspection of the drawing. The forward end of each of the arms 16 is pivotally engaged in the bifurcated portion of a bolt 17. A pair of forwardly converging blades 18, which are concavo-convex in cross section, are disposed in front of the automobile, and each blade has one of the bolts 17 secured through the intermediate portion thereof. Each of the blades has an angle member 19 secured to the inner face, slightly in rear of the bolt 17, and extending transversely between the blades, and secured to said angle members by bolts 20, in a brace rod 21, said rod holding the blades in proper position in front of the automobile. The forward ends of the blades are hinged together as at 22, whereby when the U-bolts 13 are removed the two blades may be folded together for convenience in storing or shipping. Extending rearwardly from each of the blades, at points immediately in rear of the bolts 17, are the arms 23 to which the shoes 24 are attached. Each of these shoes has its forward lower portion curved in the manner of a sled runner so that it will easily glide over the snow, and formed on the upper edge of the shoe or runner are the arms 25. These arms are formed with the longitudinal series of openings 26 for the reception of bolts 27 which also pass through said arms 23, to hold the runners in proper position, and whereby they may be adjusted to the proper height to raise or lower the scraping blades. Carried by the forward apex of the device is an eye-bolt 28, and engaged with the eye of said bolt is the forward lower end of a rod 29, the other end of said rod being connected to one end of a coil spring 30. A second rod 31 is connected to the other end of the spring and has its remaining end formed with a loop or eye 32 which is engaged on the filling tube of the radiator. A turnbuckle 33 is disposed in the intermediate portion of the rod 31 whereby the rod may be adjusted and the tension of the spring increased or de-

creased, according to the height at which the operator desires the scraper blades. By adjusting the scraper blades upwardly and downwardly, a lesser or greater portion of the snow will be scraped from the road. It is generally desirable, especially on State roads, to leave a few inches of snow for the use of sleighs, and which will readily permit the rear or traction wheels of an automobile to get a good grip to drive the automobile. This will vary, of course, according to the character of the snow, whether the same is soft or hard. In light or soft snows the depth would be greater than when the snow is of a dry or hard character. At the forward end of the scraper there is disposed an arm 34, similar to the arms 23, and adjustably secured to this arm is a runner or shoe 35.

20 Thus as the automobile is driven forward, the scraper blades scrape the snow and deflect it to the sides of the road, the blades being disposed at such a height from the ground that several inches of snow is left on the road for sleighing. This snow left on the ground, will be sufficient to permit the rear wheels of the automobile to operate properly to drive the automobile, which would have been hard, or impossible in 25 deeper snow. Thus the device serves a double purpose, first, by cleaning enough snow from the road to permit proper tractive action of the drive wheels of the automobile, and second, to leave enough snow on the 30 road to permit the use of sleighs.

15 Furthermore, by reason of the construction and arrangement of the runners, with the forward ends extending forwardly of the lower edge of the moldboard, and being

upturned in front thereof, such runners 40 will encounter any obstruction and lift the moldboard whereby the moldboard will be prevented from striking such obstruction.

It will be understood that this device is also especially adapted for use with large 45 automobile trucks, in cities to clean the snow from the streets, and in this case, the blades will be lowered so as to scrape the snow entirely from the surface of the paving.

50 What is claimed is:

A snow plow comprising a double moldboard, means for detachably supporting the plow on the front of a motor driven vehicle, inwardly extending brackets carried by the 55 inner faces and within the angle of the moldboard of the plow, runners disposed in parallel relation to each other and extending forwardly and rearwardly beneath the moldboard, vertical stems on the runners adjustably engaged with the brackets whereby the runners are capable of being raised and lowered to hold the moldboard at different distances above the ground and whereby various depths of snow will be left on the 60 ground, the forward ends of the runners being upturned in front of the wings and angle of the moldboard, and having their lower edge portions curved forwardly and upwardly, whereby the moldboard will be 65 lifted when an obstruction is reached without contact with such obstruction.

70 In testimony whereof I affix my signature in the presence of two witnesses.

HARRY H. CLARK.

Witnesses:
